UNITED STATES PATENT OFFICE.

LAWRENCE PARKER DWYER, OF CHICAGO, ILLINOIS, ASSIGNOR TO DWYER EQUIPMENT COMPANY, OF CHICAGO, ILLINOIS, A CORPORATION OF ILLINOIS.

HEATING AND VENTILATING CABINET.

Application filed August 13, 1919. Serial No. 317,188.

This invention relates generally to heating and ventilating apparatus, and particularly to apparatus of the hot blast type.

The general object of the invention is the provision of an improved apparatus designed for installation in a room as a fixture and adapted to function effectively to heat the room by circulation of heated air therein, or to ventilate the room by the circulation 10 therein of fresh air drawn from a suitable source of supply.

More particular objects of the invention reside in the provision of an apparatus of the type described which is of a compact and 15 unitary construction in the nature of a cabinet adapted for installation with facility, which may be manufactured and operated economically, and which possesses certain features of advantage whereby increased 20 efficiency in its operation and maintenance is attained.

One of the particular objects of the invention is the provision of an apparatus of the type above mentioned in which circulation 25 of air is induced by fans, the arrangement of which is such as to produce a desired circulation of heated or fresh air with a minimum expenditure of power and with minimum deterioration in the apparatus.

30 A more specific object embraces the installation of two fans adapted to discharge air currents in opposite directions, the motor for driving the fans being removed from the path of the air currents.

35 A further specific object of the invention is the provision in an apparatus of the sort specified of right and left-hand fans of the disk or screw propeller type constructed and arranged to discharge an equal amount of 40 air, and arranged so that each counterbalances the thrust reaction of the other.

Another object is the provision in an apparatus of the sort specified of a single motor directly connected to the fan wheel shafts 45 in such a manner that the weight of the wheels is not permitted to produce a deflection of the motor shaft or de-centering of the armature.

50 A specific further object of the invention consists in the arrangement of a bypass so that incoming air may be conducted to the fan wheels without entering into contact with a heating medium, to permit efficient operation when ventilation alone is desired.

55 A further purpose of the invention resides

in the arrangement of a pair of inlet openings which communicate with the outside air and the interior of the room, respectively, so that either fresh air or room air, or a mixture of fresh air and room air may be conducted to the fan wheels.

With these and other objects in view, which will appear hereinafter, preferred embodiments of the invention are described in the following specification for the purpose of 65 illustration, the scope of the invention being defined in the appended claims.

In the annexed drawings:

Fig. 1 is a sectional elevation of a cabinet constructed in accordance with my invention, the section being taken on line 1—1 of Fig. 2;

Fig. 2 is a sectional plan view of the improved cabinet;

Fig. 3 is a perspective view showing the 75 cabinet suspended from the ceiling and arranged with one of the inlet openings at the upper end of a window;

Fig. 4 is a sectional elevation of a modified cabinet, the section being taken on line 4—4 80 of Fig. 5;

Fig. 5 is a sectional plan view of the cabinet shown in Fig. 4, and

Fig. 6 is an enlarged view of the motor disclosing the manner of connecting the same 85 to the fan wheel.

Referring to Figs. 1 to 3, the cabinet, generally designated by 1, is arranged at a distance from the ceiling and suspended therefrom by rods 2. The rear end 3 of the cabinet has a rectangular cross-section and is open, said opening usually being arranged at the upper portion of a window 4, so that fresh air may enter the casing. The rear portion 3 of the cabinet is formed with 90 flanges 5, whereby the cabinet is secured in place to a wall 6. The top wall 7 of the cabinet remains in the same horizontal plane throughout its length, but the bottom wall 8 from the rear portion 3 slants downwardly, 95 as at 8, and passes into a horizontal portion 9 for a certain length; then slants upwardly, as at 10, and finally terminates in a short horizontal portion 11.

Slightly above the horizontal portion 9 of 100 the bottom, a false bottom 12 is arranged, which, together with the bottom portion 9, constitutes a bypass 13, for a purpose hereinafter further explained. The false bottom 12 serves to support a plurality of pipe coils 110

or heat radiating elements diagrammatically illustrated at 14, which are supplied with steam by means of the pipes 15, there being pipes 16 serving as a return. The side walls 5 of the cabinet at the forward end of the rear portion 3 incline outwardly, as at 17, and then pass into parallel portions 18. The front wall 19 forms a closure for the cabinet.

In conjunction with the inlet opening 20, 10 through which the fresh air enters, an aperture 21 is arranged in the bottom of the rear portion 3, which aperture permits the entrance of room air. The inlet opening 20 is controlled by a damper plate 22, arranged 15 on a spindle 23. A lever 24 is secured to the projecting end of the spindle 23 and has a depending cord at both ends, so that upon actuation of the cord in the proper manner the damper plate 22 may be swung into 20 restricting or open position for the purpose of permitting or avoiding the ingress of fresh air. At a distance to the front of the spindle 23 and below the same, a spindle 25 is arranged carrying a damper plate 26 25 provided for the control of the bottom aperture 21.

As will be seen by reference to Fig. 1, the damper plates 22 and 26 are interconnected by a link 27, the parts being so 30 arranged that when the damper plate 22 is in completely open position, the damper plate 26 completely closes the aperture 21 and vice versa. At an intermediate position of the plates both openings 20 and 21 35 are partly closed and sufficient air may enter through both openings to equal the amount of air which may enter through one of the inlet openings when restricted.

In the bypass 13, previously referred to, 40 a spindle 28 carries a damper plate 29 and a lever 30, fast to the spindle, has at both ends a depending cord to facilitate the actuation of the plate 29. The purpose of the damper plate 29 consists in permitting or preventing 45 the flow of incoming air through the bypass, as will be hereinafter further described.

At a suitable distance from the heating coils 14, a horizontal shaft 31 is suitably 50 supported in an open frame 32, the shaft carrying at both ends fan wheels 33 and 34 which are preferably, although not necessarily, Blackman propeller wheels. The wheels are right and left-hand, and are of 55 a construction and pitch to exercise equal thrust when operated to discharge air currents into the room through openings 35 and 36 provided in the side walls of the cabinet. Intermediate its ends, the shaft 31 60 carries a small pulley 37 around which a belt 38 is trained, which encompasses the motor pulley 38' of an electric motor 39, arranged outside of the cabinet. The motor 65 is supported on a platform 42 carried by longitudinal members 43 of the cabinet.

As will be seen by reference to Figs. 1 and 2, the front wall 19 has an opening closed by the door 40, which, however, is cut away at one corner for the passage of the belt 38. It will be seen that the motor being completely without the cabinet does not interfere with the propulsion of the air currents which, when heated, otherwise might cause an overheating of the motor. Attention is called to the fact that the outlet 70 openings 35 and 36 in the side walls of the cabinet are provided with deflectors 41, whereby the air currents discharged from the propeller wheels are distributed over a considerably large space. 80

The operation of the cabinet is as follows: When heating of a room is desired, the plate 22 is actuated to occupy a vertical position so as to close the opening 20 and prevent the ingress of fresh air. The plate 26 then also occupies a vertical position and room air may ingress through the opening 21 and flow past the heating coils 14 to the fans to be discharged thereby in opposite directions through the side walls of the cabinet. When the room has been heated to the desired capacity and further heating of the air by the heating coils is only necessary to maintain a certain temperature in the room 95 in view of the heat losses through the building it suffices to heat only a portion of the air circulating through the cabinet while the remaining portion may be diverted so as not to contact with the heating coils. 100

In the first instance when heating the room the damper plate is in vertical position, to force all of the air past the coils 14. To merely maintain a reached temperature, the damper plate 29 is actuated to afford a 105 passage for the portion of the air through the bypass 13, so that the heated air and unheated air mingle and are discharged by the fans. The cabinet may be used as a ventilating device and to this end both damper plates 22, 26, are arranged horizontally 110 so that the opening 20 permits the ingress of fresh air which is then distributed by the fans. When fresh air to an amount less than the full opening 20 provides is desired, then the plates 22, 26 are arranged in oblique position as shown in Figs. 1 and 4, so that simultaneously fresh and room air are drawn in by the negative pressure set up by the fans. 115

The modification shown in Figs. 4-6 is in substance the same as shown in the principal figures thus far described, with the difference that instead of providing a belt drive for the fan wheels, direct drive is provided for the wheels. To this effect the cabinet has at its forward middle portion, a housing 44 for the reception of a motor 45 which is directly connected to the shafts of the fan wheels. The presence of the housing 125 prevents any harmful effect of the heated air 130

upon the motor. In this modification also the motor is removed from the path of the air currents. The direct connection of the motor with the fan wheels would be likely to contribute to a rapid deterioration of the motor, as the weight of the fan wheels would cause a deflection of the motor shaft and a de-centering of the armature.

In order to overcome these objections, the motor shaft is connected to the fan wheels by means of a hollow tube 46 which at the outer end carries the fan wheels and at the inner end surrounds a bushing 47, arranged on the shaft. A coupling ring 48 surrounds the tube 46 and a plurality of set screws 49 ensure connection between the tube and the motor shaft. The hollow tubing forming a flexibly connected extension of the motor shaft prevents vibrations set up by the fan wheels causing any deterioration of the shaft at the motor bearing. The efficiency of the motor is contributed to materially by this arrangement of the fans as, due to the fact that the latter exercise equal thrust, their thrust reactions will counter-balance each other, thereby avoiding any loss of power through end thrust on the fan shaft. The construction therefore tends to prevent deterioration of the operating parts, and in addition the efficiency of the entire apparatus is unusually high by reason of the large space throughout which air currents are propelled. The modification in other respects is constructed and operates identical with the principal construction, so that no further reference thereto is deemed necessary.

While the drawings disclose preferred embodiments of the invention, they are merely indicative of the principle on which the invention is predicated. Various changes and alterations may be made without departing from the spirit of the invention, and I therefore do not limit myself to the details exactly as shown, but want to include all modifications constituting departures within the purview of the invention as defined by the following claims.

I claim:

1. In an apparatus of the class described, in combination, a cabinet adapted for installation in the room to be heated, said cabinet being provided with an air inlet opening and with oppositely disposed air outlet openings, propeller fans journaled in the cabinet in association with the outlet openings, a radiator housed in the cabinet between the inlet opening and the outlet openings, and a motor

supported by said cabinet and having operative connection with said fans whereby the latter may be actuated to draw air through the radiator and expel it directly into the room through the outlet openings, said motor being exposed to the air of the room outside the cabinet.

2. In an apparatus of the class described, in combination, a cabinet adapted to be installed in the room to be heated, said cabinet being provided with an air inlet opening and with oppositely disposed air outlet openings, propeller fans associated with the outlet openings, a radiator housed in the cabinet between the inlet opening and the outlet openings, a motor supported by the cabinet substantially co-axially with the fans, and flexible connections operably joining the fans and motor shaft whereby the former may be actuated to expel air from the cabinet directly into the room.

3. A heating and ventilating apparatus comprising, in combination, a cabinet adapted for installation in the room to be heated, said cabinet being provided with an air inlet and air outlet openings discharging directly into the room in opposite directions, a radiator housed in the cabinet between the inlet opening and the outlet openings, fans mounted in the cabinet at the oppositely discharging outlet openings and adapted to expel air from the cabinet into the room, means for actuating the fans, and means providing a by-pass within the cabinet whereby air may be diverted around the radiator from the inlet to the fans.

4. In an apparatus of the class described, in combination, a cabinet adapted to be installed in the room to be heated, said cabinet being provided with an air inlet opening and with air outlets opening in opposite directions, propeller fans associated with said outlet openings, a radiator housed in the cabinet between the inlet opening and the outlet openings, a motor compartment disposed in the cabinet between the propeller fans, said motor compartment being closed to air within the cabinet and open to air outside the cabinet, and a motor housed in said motor compartment and operably connected to the fans, whereby the latter may be actuated to draw air through the radiator and expel it through the outlet openings.

Signed at 36 West Randolph Street, in the county of Cook and State of Illinois, this 7 day of August, 1919.

LAWRENCE PARKER DWYER.
